[57] CLAIM

The ornamental design for a rear fender flare for vehicles, as shown and described.

DESCRIPTION

FIG. 1 is a front elevational view of the rear fender flare for vehicles, showing my new design, shown in its position of use;

FIG. 2 is an enlarged front elevational view thereof;

FIG. 3 is an enlarged rear elevational view thereof;

FIG. 4 is an enlarged top plan view thereof;

FIG. 5 is an enlarged bottom plan view thereof;

FIG. 6 is an enlarged left side elevational view thereof; and,
FIG. 7 is an enlarged side elevational view thereof.

The broken line showing of environment is for illustrative purposes only and forms no part of the claimed design.
